UNITED STATES PATENT OFFICE.

WILLIAM DIETER, OF BROOKLYN, NEW YORK, ASSIGNOR TO E. W. BLISS COMPANY, OF BROOKLYN, NEW YORK, A CORPORATION OF WEST VIRGINIA.

GYROSCOPIC MECHANISM.

1,322,232.

Specification of Letters Patent. Patented Nov. 18, 1919.

Application filed February 26, 1918. Serial No. 219,202.

To all whom it may concern:

Be it known that I, WILLIAM DIETER, a citizen of the United States of America, residing in the borough of Brooklyn, county of 5 Kings, city and State of New York, have invented certain new and useful Improvements in Gyroscopic Mechanism, of which the following is a specification.

This invention relates to means for spinning up the gyroscope and for maintaining 10 it in rotation. It is especially designed to meet the requirements of gyroscopes for automobile torpedoes.

In such torpedoes the gyroscope is spun 15 up either by a clock-work or spring motor, or by the action of compressed air upon a turbine. The latter is the preferable means. It is important that the gyroscope be spun up to full speed during a very brief time, so 20 that it may be brought to speed and unlocked, and thereby set free, while the torpedo is either still guided within the launching tube or still retains the direction or aim given it in the launching tube, so that this 25 direction may be effectually impressed upon the gyroscope. For this purpose in an air-spun gyroscope high pressure air is employed, that is to say, air at full flask pressure of 2,250 pounds per square inch, or upward. 30 The flow of compressed air is shut off upon the unlocking of the gyroscope by the closing of a valve, these operations being timed by a timing or counting-down mechanism which acts after the spinning-up turbine 35 has executed a prescribed number of revolutions.

A suitable construction of gyroscope and spinning mechanism as thus described is set forth in the patent of Leavitt, No. 1,185,210, dated May 30, 1916.

When a gyroscope is thus spun up and unlocked, it continues running during several minutes under impulse of the momentum stored up in the fly-wheel, but as the fly-wheel 45 is gradually slowing down, the directive energy of the gyroscope is constantly diminishing. It is important that the speed should not fall below a certain minimum prior to the end of the run of the torpedo. 50 Torpedoes are now built to have a far greater range than formerly, and this fact increases the difficulty of insuring that the gyroscope shall not fall below the minimum required speed during the run. To prevent 55 this, it has been proposed to apply an electro-

motor to keep the gyroscope up to speed during the run of the torpedo after the initial spinning up of the gyroscope. A suitable construction for this purpose is set forth in the Leavitt Patent No. 1,145,025, of July 6, 1915.

The present invention has for its object to accomplish the same result by means that are more in accord with standard torpedo practice, and whereby the use of electro-magnetic expedients may be dispensed with.

To this end the present invention provides means whereby the gyroscope after being initially spun up in the ordinary manner may be maintained at speed by the turbine 70 driving effect of compressed air. In the preferred development of the invention high pressure or flask pressure air is employed for initially spinning up the gyroscope, and low pressure air is employed for the subsequent driving of the gyroscope, so as to keep it up to speed.

The preferred construction is set forth in the accompanying drawings, wherein;

Figure 1 is a side view of the rear or stern portion of a torpedo, being partly in vertical mid-section, wherein the parts are drawn in a somewhat diagrammatic manner to illustrate the invention.

Fig. 2 is a sectional elevation of the gyroscope and starting mechanism, the sectional portions being in longitudinal mid-section.

Fig. 3 is a front elevation looking toward the stern, partly in section on the line 3-3 in Fig. 2, showing the spinning-up turbine 90 in its active relation.

Fig. 4 is a fragmentary transverse section on the line 4-4 in Fig. 2, showing the turbine means for maintaining the drive of the gyroscope.

Fig. 5 shows in plan two graduating or adjusting disks.

Fig. 6 is a section of two parts in Fig. 4 removed.

Referring to Fig. 1, A is the shell or hull 100 of the torpedo, of which B is the propeller shaft or shafts driving in contrary directions the two screws C, and D is the lateral steering rudder which through the usual connections (not shown) is operated by a 105 steering engine or servo-motor E which is mounted as usual on the gyroscope casing F. The compressed air from the flask or reservoir when the starting valve (not shown) is open passes by pipe a to the reducing valve 110

- 2
- G and from the low pressure side of the latter by pipe *b* to the superheater H, and thence by pipe *c* to the engine or motor which drives the shafts B (this motor being 5 commonly a turbine as is well understood, and for simplicity is not here shown). From the high pressure side of the reducer G a small tube *d* is led in the usual manner to the spinning-up mechanism of the gyroscope.
- 10 From the low pressure side another small tube *e* is led to the gyroscope casing and conducts the air at substantially the pressure at which it is passed through the superheater and fed to the engine to the continuous 15 drive turbine of the gyroscope, as will be explained.

Referring to Fig. 2, the gyroscope casing F incloses in the usual manner the gyroscope J, which latter is of the well understood 20 stood construction comprising a fly-wheel K pivoted by ball bearings or otherwise in an inner ring *f* which in turn is pivoted in an outer ring *g*, and the latter in turn is pivoted on a vertical axis in a frame *h* which 25 comprises the fixed shell or casing of the gyroscope, and which is located in the usual manner within the outer casing F. Before spinning up, the gyroscope rings are held fast by a locking bolt *i* in the usual manner 30 (being shown unlocked in Fig. 2). For spinning up the gyroscope, a turbine L is provided, the shaft of which turns in a sliding sleeve M and carries a pinion *j* which meshes with either of two pinions *k* on the 35 fly-wheel axis. The high pressure air tube *b* communicates through a valve *m* with a passage *n* leading the air to jet nozzles *p* which direct it against the turbine as shown in Fig. 3, the turbine at this time being in 40 the position shown in dotted lines in Fig. 2. At the end of the spin the operation of a lever *q* displaces slide M and turbine L and at the same time closes the valve *m* and withdraws the lock *i*, thus shutting off the air 45 and freeing the gyroscope. By reason of the high pressure of the air, this spinning-up operation is very forcible, and the fly-wheel is brought up to speed almost instantaneously.

50 For maintaining the air propulsion of the gyroscope, it is best to make the fly-wheel K serve as the rotor of a turbine, for which purpose it is shown as constructed with teeth or buckets *r*, which receive the impact 55 of jets of air from nozzles *s*, as best shown in Fig. 4. The air is here shown as coming by the tube *e*, which leads into a chamber *t*, at the lower pivotal bearing of the outer ring *g* of the gyroscope; from chamber *t* 60 the air passes up through a conduit into a chamber *u*, whence it issues through the jet nozzles *s* and impinges against the buckets to drive the fly-wheel. The nozzles *s* are centered along a plane which intersects the 65 vertical pivotal axis of the ring *g*, and hence

the reaction of the jets has no tendency to turn this ring to either side, and consequently exerts no disturbing effect upon the gyroscope. The action of the low pressure air is simply to overcome the frictional or other retardation which tends to slow down the gyroscope, and thereby to keep it up to normal energy.

While the construction of the maintenance turbine may be greatly varied, that shown is deemed preferable. The tube *e* leads into the hub *h'* into which is screwed the lower ball bearing step *v*, which forms the race-way for the balls of the lower ball bearings. The air may pass through any one of a series of bored passages into the chamber *t*, which is hollowed out in the step or plug *v*, and closed by a special screw plug *w*. The air from *t* flows up through the ball bearing passing through an inner tube or nozzle *x*, shown best in Fig. 6, and through a passage *y* in the ball bearing cone, and hence into the chamber *u*. The air thus enters axially and in a way which cannot disturb the ball bearing or the gyroscope.

It is important to be able to adjust the pressure at which the air is fed to the jet nozzles *s*. This might be done, of course, by introducing any sort of regulating valve at any suitable point in the tube *e*; but it is more conveniently and simply accomplished by the means shown which comprises a disk *z*, of which two examples are shown in Fig. 5, and which partly closes the exit from the chamber *t* into the tube *x*. This disk *z* has a central hole which constricts the flow of air, and the size of which determines the effective air pressure at the nozzles. By providing a series of these disks with central ori- 100 fices of graded sizes (two examples only being shown) the pressure of the air may be regulated to a nicety as determined by experiment. The plug *w* has projecting lugs or fingers which as the plug is screwed home bear against the disk *z* and hold it tightly in place.

It is not to be assumed from the detailed description of the construction herein shown, that the invention is limited to such specific construction, since it is susceptible of a considerable range of variation. For example, the specific spinning-up mechanism is not essential to the invention; nor is the specific turbine construction for maintaining the gyroscope at speed essential, 115 since any other pneumatic means adaptable to the purpose may be substituted. It is practically important that the means for maintaining the gyroscope in rotation shall be so constructed as not to exert any disturbing effect upon the gyroscope and such as not to interfere with the free turning of its gimbal rings upon their pivots.

What I claim is:

1. In a torpedo comprising a source of 120

high-pressure air, a pressure reducer, a steering mechanism and a gyroscope controlling such mechanism, the combination therewith of pneumatic means for initially 5 spinning the gyroscope fed from said high-pressure source, and pneumatic means for subsequently maintaining the gyroscope in rotation fed from the reduced pressure side of said reducer, whereby the gyroscope 10 is initially spun by air at high pressure, and is kept spinning by air at low pressure.

2. The combination of claim 1, with means for controlling the reduced pressure fed to the maintaining means, to thereby 15 determine the driving effect of the latter.

3. The combination of claim 1, with means interposed in the conduit between such pressure reducer and pneumatic maintaining means for further reducing such 20 pressure before feeding it to said maintaining means.

4. The combination of claims 1 and 3, such reducing means consisting of a removable perforated diaphragm adapted to be 25 introduced in the air conduit, which may be replaced by a similar diaphragm having a perforation of different area.

5. The combination of claims 1 and 3, such reducing means comprising a chamber 30 in the air conduit, a cap closing said chamber, and a removable disk inserted in said chamber and held therein by said cap, said disk having a perforation traversed by the air.

35 6. In a torpedo comprising a source of

high pressure air and means for delivering air at materially reduced pressure, a steering mechanism and a gyroscope controlling such mechanism, with pneumatic means for initially spinning the gyroscope fed from said 40 high pressure source, the combination therewith of pneumatic means for subsequently maintaining the gyroscope in rotation fed from air at such reduced pressure, and means for further diminishing the pressure of such 45 air, whereby to vary the effect of such pneumatic maintaining means.

7. The combination of claim 6, the means for further diminishing such pressure comprising a removable perforated diaphragm 50 introduced in the air conduit and adapted to be replaced by a similar diaphragm having a perforation of different area.

8. The combination of claim 6, such means for further diminishing the pressure 55 comprising a chamber in the air conduit, with a cap for closing such chamber, and a removable disk in said chamber having a perforation traversed by the air.

9. The combination of claim 6, such 60 means for further diminishing the pressure comprising a chamber in the air conduit, a cap closing said chamber, and a removable disk inserted in said chamber and held therein by said cap, said disk having a per- 65 foration traversed by the air.

In witness whereof, I have hereunto signed my name.

WILLIAM DIETER.
